ICE PICK

Myron J. Zimmer, Chicago, Ill., assignor to The
Edward Katzinger Company, Chicago, Ill., a
corporation of Illinois

Application July 21, 1938, Serial No. 220,464

1 Claim. (Cl. 83—62)

This invention relates to a cap adapted to be mounted on the butt end of handles for tools and is especially applicable to a handle for an ice pick or the like, in the use of which the butt end of the handle is frequently employed for cracking and shattering a piece of ice.

It is an object of this invention to provide a handle cap with a peripheral projection with which the usual cracking of ice can be readily done without damaging the exposed portion of the handle and which at the same time provides a cap of such cross section that it will not readily roll when laid down on a sloping surface.

With the above and other objects in view, as will be apparent, this invention consists in the construction, combination and arrangement of parts all as hereinafter more fully described, claimed and illustrated in the accompanying drawing, wherein:

Fig. 1 is a top view of a handle cap embodying the features of this invention.

Fig. 2 is a side elevation of an ice pick, with parts in section to illustrate details of the handle cap shown in Fig. 1 and the handle in completed assembly.

Reference being had to the drawing, 10 designates the handle of an ice pick or similar tool, having any suitable shape and size and being formed from any adaptable material, preferably and usually of wood. A pointed pick blade 11 of conventional length and equipped with the usual shank portion is attached to the handle 10 by having the shank of the blade 11 embedded in the handle 10.

The end of the handle 10 adjacent the blade 11 is preferably shouldered as at 12, and has a ferrule 13 mounted thereon. The outer extremity of the ferrule 13 is closed by a face which covers the end of the handle 10 and through which the shank of the blade 11 must pass to become embedded in said handle.

A cup shaped member or cap 15 formed of sheet metal or any other suitable material is mounted on the butt end 16 of the handle 10. The internal contour of the cap 15 is preferably such as to make a driving fit on the butt end of the handle while the outside of the cap is provided with faces defining a plurality of corners extending lengthwise of the handle 10. Rigid connection between the cap 15 and the butt end 16 of the handle may be further established by means of a screw 17 passed through the base of the cap 15 and embedded in the body of the handle as more clearly shown in Fig. 2.

At its lower edge or periphery, the cap 15 terminates in an annular flange 18 projecting outwardly from the body of the handle 10 and substantially perpendicularly to the longitudinal axis of the handle, to provide a relatively thin edge

portion 19 in outwardly spaced relation to the corners of the cap extending lengthwise of the handle 10. The edge portion 19 may be treated or trimmed as shown in the drawing to present projections 20 at peripherally spaced points of the flange 18, which gives to the edge 19 a polygonal outline with corners projecting far enough to serve as anti-rolling corners when the tool is laid down on a sloping surface.

In operating the tool for severing portions of ice from a larger cake, the butt end of the handle 10 readily fits the palm of the user's hand and the flange 18 provides an undersurface against which the thumb and fingers of the hand may press to firmly grip the handle 10 without unduly cramping the fingers.

In operating the tool for further cracking or shattering the severed portions of the larger cake of ice, the tool may be grasped by the blade 11 and thus the butt end of the handle equipped with the cap 15 may be employed for striking the ice. It will be apparent that the relatively thin edge 19 of the flange 18 aids in shattering the ice portion. Furthermore, the impact of the edge 19 with the ice will not injure the finish of the handle 10 adjacent to the cap 15 because of the distance between the edge 19 and the body of the handle as afforded by the width of the flange 18.

From the foregoing it will be readily manifest that the handle cap provided by this invention protects the handle from injury when the butt end thereof is used for shattering severed portions of a larger cake of ice, affords a good gripping means for the hand of a user when used for severing portions from a larger cake of ice, and at the same time provides a cap of such cross section that the tool will not readily roll when deposited on a sloping surface.

It will be obvious that various modifications may be made by those skilled in the art in the details of the construction illustrated in the drawing and described in detail above within the principle and scope of the invention as expressed in the appended claim.

What is claimed is:

In an ice pick, the combination with a handle comprising a leading end and a relatively enlarged butt end, a pick blade having a shank portion embedded in and projecting forwardly from said leading end of the handle, a cap of sheet metal or the like having an internal contour adapted to make a tight fit on the butt end of the handle to form a striking head, and means presenting a relatively sharp edge of polygonal outline in proximity to said striking head comprising an annular flange projecting laterally and outwardly from the forward edge of said cap.

MYRON J. ZIMMER.
